CLAIM

The ornamental design for a jar for a cosmetic composition, as shown and described.

DESCRIPTION

FIG. 1 is a perspective view of an embodiment of jar for a cosmetic composition, embodying our new design;

FIG. 2 is a front view thereof;

FIG. 3 is a back view thereof;

FIG. 4 is a left side thereof;

FIG. 5 is a right side view thereof;

FIG. 6 is a top-view thereof; and,

FIG. 7 is a bottom view thereof.

The broken lines illustrate structure or features that form no part of the claimed design.

Any patent application or patent to which this application claims priority or benefit thereof, is hereby incorporated herein by reference in its entirety.

1 Claim, 7 Drawing Sheets
